ALVARO S. KROTZ, OF JANESVILLE, WISCONSIN, ASSIGNOR TO JANESVILLE MACHINE COMPANY, OF JANESVILLE, WISCONSIN, A CORPORATION OF WISCONSIN.

LISTER PLOW.

1,413,281.

Specification of Letters Patent. Patented Apr. 18, 1922.

Application filed May 26, 1919. Serial No. 299,761.

To all whom it may concern:

Be it known that I, ALVARO S. KROTZ, a citizen of the United States of America, and a resident of Janesville, Wisconsin, 5 have invented a certain new and useful Improvement in Lister Plows, of which the following is a specification.

This invention relates to wheeled plows, and more particularly to those of the type 10 ordinarily called listers, being equipped with one or more lister plows, preferably two, arranged side by side, as in the case of what are commonly called two-row listers or wheat land listing plows, such as those 15 employed for ridging the soil in the ordinary and well known manner.

Generally stated, the object of the invention is to provide a lister plow of the foregoing general character, having certain improvements which will tend to insure greater 20 strength and rigidity than heretofore; to provide improved means for controlling the working depth of the plows; and to provide certain details and features of construction 25 and combinations tending to increase the general efficiency and the desirability of a two-row lister plow of this particular construction.

To the foregoing and other useful ends 30 the invention consists in matters hereinafter set forth and claimed.

In the accompanying drawings—

Fig. 1 is a plan of a two-row wheat land 35 listing plow embodying the principles of the invention.

Fig. 2 is a side elevation of said plow, showing one of the front disks partly broken away to bring into view the means by which the front portion of the frame is supported 40 by the disks.

Fig. 3 is a fragmentary detail view showing a portion of the frame construction.

Fig. 4 is an enlarged detail section on line 45 4—4 in Fig. 1.

Fig. 5 is an enlarged detail view showing the connection between the frame and the front end of one of the plow beams.

Fig. 6 is an enlarged detail section on line 50 6—6 in Fig. 1.

Fig. 7 is an enlarged detail section on line 55 7—7 in Fig. 1.

Fig. 8 is an enlarged detail section on line 8—8 in Fig. 1.

As thus illustrated, the invention 60 comprises a rigid frame formed by side bars 1

which converge to the casting 2 at their forward ends, being held together by the bolts 3 which extend through said casting, and it being observed that the latter is an arm projecting from the rear side of the 60 vertically disposed sleeve or swivel bearing 4, as will hereinafter more fully appear. The parallel rear end portions 5 of the two side bars are rigidly connected together by a transversely arranged angle iron 6 rigidly 65 secured thereto by brackets 7, the latter having bolts 8 which extend through the side bars, and bolts 9 which extend downwardly through the transverse bar. Thus a substantially V-shaped frame is formed which is 70 very strong and rigid.

The front end of the frame thus formed is supported by a pair of disks 10 suitably mounted on the lower end of the pivot post 11, which latter extends upwardly through 75 the sleeve or swivel bearing 4, whereby the two disks form a sort of truck which turns about a vertical axis to steer the two-row lister plow to the right or the left. The clevis 12 is rigid with the post 11 and is formed 80 with holes 13 to receive the bolts 14 by which the tongue or pole 15 is pivotally supported on the clevis in position to swing up and down in the usual and well known manner. In this way the pole controls the front of 85 the truck and turns the disks 10 to the right or the left to guide the plow in either direction.

The two plows 16 are the usual or well known form, being the ordinary double mold board or lister plows employed for purposes of this kind. These plows have forwardly extending beams 17 provided with brackets 18 which are secured to the beams by bolts 19, and bolts 20 which extend downwardly 90 through openings 21 in the transverse bar 6 which forms a part of the rigid main frame. In this way, and by adjusting the bolts 20 from one hole 21 to another, the distance between the two plows can be changed or 95 varied to suit the requirements. A transverse angle iron beam or bar 22 is secured by brackets 23 to the under side of the frame side bars 1, at a point immediately 100 in rear of the casting 2, so that the end portions of this angle iron 22 project for some distance, being provided with holes 24 to receive the bolts 25 by which the brackets 26 are connected to the angle iron bar 22, these brackets 26 being connected by bolts 110

27 with the front end portions of the plow beams 17, whereby the latter are rigidly and firmly supported on the main frame.

The main frame is provided with a seat 5 28 mounted on the spring bar or support 29 which is secured at its lower end to the middle portion of the transverse bar 6, the seat being preferably in position to enable the driver to place his feet on the trans- 10 verse bar 22 when the plow is in use.

For the purpose of supporting the plows in the rear end of the body frame, crank axles 30 are provided and mounted to turn in bearings 31 on the main frame, and in 15 bracket bearings 32 suitably secured to the transverse bar 6; and it will be seen that the crank arms 33 of these axles extend forward and downward to the out-turned spindles 34 upon which are mounted the vehicle 20 wheels 35 which support the body frame and plows. The bracket bearings 32 are provided with racks 36, and hand levers 37 are keyed to the crank axles 30 by means of removable pins 38, or in any suitable manner. The crank axles have holes 39 at different points in the length of each axle to receive said pins, so that these axles can be adjusted endwise in their bearings to change or vary the distance between the two vehicle 25 wheels. Thus each hand lever 37 engages one side of a bracket bearing 32, to prevent endwise displacement of the axle in one direction, and an adjustable collar 40 engages the same bearing at the other side, these collars being adjustably held on the axles by beams similar to those used for keying the levers to the axles; or, of course, said levers and collars can be held in place by ordinary set screws if desired. Each lever has 30 a locking device 41 for engaging the adjacent curved rack 36, and these locking devices are controlled by short handles 42 pivoted on the ends of the hand levers. In this way, by unlatching the hand levers from 35 the racks 36, the two hand levers can be employed by the driver for rocking the axles 30 in their bearings, and for thereby raising and lowering the plows. In order to sink the plows into the ground, the two hand levers 40 are unlatched from the racks and allowed to swing backward, and when the plows are the desired distance in the ground, the depth can then be maintained by latching the hand levers to the racks. When it 45 is desired to raise the plows out of the ground, the two hand levers are pushed forward. Springs 43 connect the levers 37 with the front transverse bar 22, and help to raise the plows out of the ground when the hand levers are pushed forward. These springs, 50 however, are not so strong but that the levers 37 can be easily pulled backward when it is desired to lower the plows into the ground.

65 In order that the front end of the body

frame may be adjusted up and down, a collar 44 is provided on the post 11, being adjustably held thereon by a set screw 45, and being provided with a hook 46 for engaging the flange 47 formed on the lower end of 70 the sleeve or swivel bearing 4, whereby the sleeve 4 is supported by the collar 44, and is prevented by said hook from rising on the post. In this way, as stated, the front end of the main body frame can be readily 75 raised and lowered to suit the requirements of different circumstances.

The two forwardly converging side bars 1 and the rear transverse bar 6 form a rigid main body frame, the forward ends of said 80 bars 1 being rigidly connected together, so that a forwardly tapered main frame is provided. The rear ends of these side bars 1, and the bar 6, support the bearings in which the crank axles 30 are supported, so that the 85 cranks 33 extend forward, whereby the two plows are raised and lowered when the main frame is raised and lowered by the rocking of the crank axles. The driver pushes forward on the levers 37 to raise the body 90 frame, and the seat 28 is arranged in position to facilitate this manipulation of the hand levers. The transverse bar 22 provides a forward point of support for each plow beam 17, of course, and serves also to brace 95 the forwardly tapered body frame, whereby the said plow beams and the body frame form a very rigid structure which is adapted to advantageously withstand the strains incident to the action of the plows in the 100 ground while the machine is moving forward. Even without the transverse bar 22, the body frame is strong and rigid and complete, and this bar adds to the strength and 105 rigidity of the body frame and provides for 110 the convenient support of the forward ends of the plow beams, in the manner shown and described.

What I claim as my invention is:—

1. In an agricultural implement, the combination of means forming a rigid body frame which tapers toward its front end, means to support the forward end of said frame, wheels to support the rear end of said frame, implement beams extending longitudinally of said frame, a draft member extending transversely of the tapering forward portion of said frame, rigidly secured thereon to brace the frame a distance in rear of the forward end thereof, means for connecting the forward ends of said implement beams to said transverse draft member, means for connecting the rear portions of said implement beams with the rear portion of the main body frame, means for controlling said wheels to raise and lower the body frame and said implement beams, and implements secured to the rear end portions of said beams.

2. A structure as specified in claim 1, said 130

main body frame having a transverse rear end member which extends under said implement beams.

3. A structure as specified in claim 1, said transverse member extending under the main body frame, so that the opposite end portions of said member extend beyond the frame, the implement beams being connected to these projecting end portions.

10 4. A structure as specified in claim 1, said main body frame comprising a transverse rear end member, forwardly converging side bars rigid with said transverse draft member, means to rigidly connect the forward ends of said converging side bars together, and means to rigidly connect the side bars to the end portions of said transverse rear end member.

20 5. A structure as specified in claim 1, said implements for the rear ends of said beams consisting of a double mold-board lister plow for each beam, said plows being spaced a distance apart.

25 6. In an agricultural implement of the class described, the combination of a main body frame having forwardly converging side bars, a vertically disposed socket secured between the forward end portions of said bars and forming a swivel bearing at the forward end of said frame, a pivot post extending upwardly through said sleeve, said post being adapted to turn or oscillate in said sleeve, means traveling on the ground to support the lower end of said pivot post, 35 means disposed below the frame and whereby said sleeve is adjustable up and down on said post, and is held in adjusted position thereon, a clevis rigid with the upper and lower end portions of said post, and a draft 40 connection attached to said clevis.

7. In an agricultural implement of the class described, the combination of a main body frame, a pair of lister plows having beams each supported at front and rear 45 points by said frame, means to support the forward end of said frame, crank axles disposed behind the rear points of support for said beams and mounted in alinement at the rear end of said frame, each axle having a 50 forwardly extending crank arm, a vehicle wheel for each crank arm, and means including hand levers secured to the crank axles to control said wheels, and to thereby raise and lower the plows out of and into the ground.

55 8. In an agricultural implement, the combination of forwardly converging side bars, a rear transverse bar rigidly secured to the rear end portions of the side bars, means to connect together the forward end portions of 60 the side bars, so that a rigid and forwardly tapered main body frame is provided, bearings on the rear end portions of the side bars, bearings on said transverse bar, crank axles mounted in said bearings, with the cranks of

said axles extending forward at opposite 65 sides of the body frame, and an implement carried by the body frame and adapted to enter the ground when the frame is lowered, in combination with a transverse bar rigidly secured to the forward portion of said body 70 frame, and means to connect this forward transverse bar to said implement.

9. In an agricultural implement, the combination of forwardly converging side bars, a rear transverse bar rigidly secured to the 75 rear end portions of the side bars, means to connect together the forward end portions of the side bars, so that a rigid and forwardly tapered main body frame is provided, bearings on the rear end portions of the side bars, bearings 80 on said transverse bar, crank axles mounted in said bearings, with the cranks of said axles extending forward at opposite sides of the body frame, and an implement carried by the body frame and adapted to 85 enter the ground when the frame is lowered, said implement comprising a plow having a beam which extends forward over said rear transverse bar at one side of said body frame, and a similar plow mounted at the 90 other side of said body frame, together with a transverse bar rigidly secured to the under side of the forward portion of said body frame to brace the latter and provide a forward support for the front ends of the plow 95 beams.

10. In an agricultural implement, the combination of a main frame comprising transverse front and rear members spaced apart 100 a distance, side members converging forward from the outer ends of said rear transverse member and having their front ends connected together a distance ahead of said front transverse member, means to rigidly connect said transverse member, to the converging side members, so that the ends of the front transverse member project from the frame at opposite sides thereof; implement beams supported on the rear transverse member at points between said converging 110 side members and connected at their forward ends to the projecting end portions of the front transverse member; supporting wheels for the rear end of said body frame; and draft means for the front end of said implement. 115

11. A structure as specified in claim 10, and means whereby to vary the distance between the implement beams.

12. A structure as specified in claim 10, 120 and a wheel truck to support the front end of said forwardly tapered body frame.

13. A structure as specified in claim 10, comprising crank axles for said wheels, and means to rock said axles to raise and lower 125 the implement.

Signed.

ALVARO S. KROTZ.
